(74) Attorney, Agent, or Firm — Andrew Malarz, Esq.

(57) **CLAIM**

The ornamental design for an end cap for securing and releasing spatual finishing blade, as shown and described.

DESCRIPTION

1.1 is a right side elevation view of an end cap for securing and releasing spatual finishing blade showing my new design in accordance to a first embodiment;

1.2 is a left side elevation view thereof;

1.3 is a perspective view thereof;

1.4 is an exploded perspective view thereof;

1.5 is an enlarged bottom perspective view thereof showing only one side of the end cap; the opposite end cap, which is also a part of the claimed design, is not shown in this view.

2.1 is a right side elevation view of an end cap for securing and releasing spatual finishing blade showing my new design in accordance to a second embodiment;

2.2 is a left side elevation view thereof;

2.3 is a perspective view thereof;

2.4 is an exploded perspective view thereof;

2.5 is an enlarged bottom perspective view thereof showing only one side of the end cap; the opposite end cap, which is also a part of the claimed design, is not shown in this view. The broken line showing of the spatula finishing blade is provided for the purposes of illustrating environmental structure and forms no part of the claimed design.
